ADJUSTABLE NECKTIE HOLDER

Filed Nov. 13, 1929

Paul Kraft

INVENTOR

By *Paul Kraft*

ATTORNEY

UNITED STATES PATENT OFFICE

PAUL KRAFT, OF NEW YORK, N. Y.

ADJUSTABLE NECKTIE HOLDER

Application filed November 13, 1929. Serial No. 406,744.

This invention relates to improvements in neckties, particularly to holders for neckties allowing the formation of the knot and necktie by sewing its material about a holder avoiding the tedious and sometimes vexing knotting of a necktie.

It is the principal object of my invention to provide a necktie holder allowing a ready attachment of the tie to a collar button or removal therefrom.

Another object of my invention is the provision of a necktie holder of comparatively simple and inexpensive make, yet durable and efficient in operation, allowing its adjustment to collars of varying heights.

A further object of my invention is the provision of a necktie-holder, the movably connected members of which are normally spread apart by means of a spring and provided with inner recesses allowing a securing of the holder over the shank of a collar button by releasing the pressure on said spring.

These and other objects of my invention will become more fully known as the description proceeds, and will then be specifically defined in the appended claims.

In the accompanying drawings forming a material part of this disclosure:

Fig. 1 is an inner or rear view of a necktie equipped with my novel holder, constructed according to my invention.

Fig. 2 is a detail rear view of the holder.

Fig. 3 is a side elevation thereof.

Fig. 4 is a front view of the holder.

Fig. 5 is a section through the same on line 5-5 of Figure 3.

As illustrated, a necktie 10 of any desired material and color, preferably of the ready to wear type has the side edges of the material turned to the rear and stitched together as indicated at 11.

The knot 12 of the tie is preferably formed over a holder, generally designated 13 and constructed as follows: Two preferably metal members 14 and 15 are formed at their rear with oppositely disposed longitudinally extending flanges each provided with alternating oppositely disposed larger recesses 16, 50 and smaller recesses 17 for the engagement

of the shaft 18 of a collar button 19, as indicated in Figure 5, and as will hereinafter be more fully explained.

The material of the lower ends of the members 14 and 15 is formed at their rear into inwardly directed, overlapping tongues 21 and 22, while similar overlapping and inwardly directed tongues 23 and 24 are formed from the material of members 14 and 15 at the front.

The ends of a substantially vertical bolt or pin 25 extend through the overlapping tongues 21, 22, and 23, 24, respectively and an upper head 26 and a lower head 27 at the pin ends limit the vertical displacement of the pin, while allowing a certain relative movement between the tongues of each pair.

The head 26 engages also and bears against the lower end of a centrally located and downwardly extending branch 28 of the holder over which the knot is to be formed from the material of the necktie which for this purpose is made with two upper tongues 29, 30 extending in opposite directions from the branch 28 and bent out of the plane thereof towards the rear.

Between the pairs of tongues 23, 24, and 21, 22, a spring 31 is wound about pin 25, the ends of which, 32, 33, respectively, engage the inner walls of the bent ends 20 of members 14 and 15 tending to press the same apart.

Holes 34 in the side faces of members 14 and 15 respectively allow the passage of threads for forming and securing the material of the necktie about the holder.

My device operates as follows:

After the knot of a tie has been formed by sewing the material about the holder the lower ends 20 are gripped by the fingers of the user and pressed against one another against the action of the spring 31, thus separating the inner rear edges of members 14 and 15 for allowing the passage of the front end of a collar button therethrough if now the pressure on the spring ends is released the shank 18 will be engaged by the closing members 14, 15 in the recesses thereof and will securely hold the necktie on the collar button, an adjustment of the tie to the different heights

of collars is made possible by enganging the collar button in the various superposed recesses in the members.

It will be understood that I have disclosed the preferred form of my invention only and that I may make such changes therein as are warranted by the scope of the appended claims without departure from my invention.

Having thus described my invention, what I claim as new and desire to secure by Letters Patent is:

1. A necktie holder comprising a pair of clamp members having upper rear flanges recessed at their oppositely disposed inner ends for engagement with the shank of a collar button, means for pivotally connecting said members, a means for normally pressing the lower ends of said members apart to close the upper flanges about the shank of said collar button, and a three-branched upper former connected to said holder allowing the formation of a knot of the necktie material about the same, said members provided with holes for stitching the material to the holder.
2. A necktie holder comprising a pair of clamp members having upper rear flanges recessed at their oppositely disposed inner ends for engagement with the shank of a collar button, a pair of rear end tongues formed with said members overlapping one another, and a pair of frontal overlapping tongues formed with said members, a vertical pin extending through said overlapping tongues, heads at the ends of said pin allowing a limited relative motion of the tongues of each pair, and a three-branched upper former having one of its branches beneath the upper head on said pin and its other branches laterally extending from said first named branch at an inclination thereto for allowing the formation of a knot in the necktie material about said former, said clamp members provided with holes for stitching the material of the necktie to the holder.

In witness whereof I have signed my name to this specification.

PAUL KRAFT.
